Primary Examiner—B. J. Bullock*Assistant Examiner*—Richelle Shelton*Attorney, Agent, or Firm*—Banner & Witcoff, Ltd.[57] **CLAIM**

The ornamental design for a wall structure for a nestable crate, as shown and described.

DESCRIPTION

FIG. 1 is a perspective view of a wall structure for a nestable crate in accordance with my new design, the perspective view from the opposite end being a mirror image thereof; FIG. 2 is a side elevational view thereof, the opposite side elevational view being identical; FIG. 3 is an end elevational view thereof, the opposite end elevational view being identical; FIG. 4 is a cross sectional view thereof taken along lines 4—4 of FIG. 2; FIG. 5 is a cross section thereof taken along line 5—5 of FIG. 3; FIG. 6 is a perspective view thereof, shown nested with an identical wall structure and crate floors in broken lines; and, FIG. 7 is a perspective view thereof, shown with bottles and crate floor in broken lines. The broken line showing of a crate floor, an identical wall structure nested with the claimed wall structure, and the bottles are for illustrative purposes and form no part of the claimed design.
